[57] ABSTRACT

A full bore drag type well drilling bit including a bit body comprised of a generally non-frangible metallic material. The bit body has an operating end face defined by said metallic material to include a plurality of upsets each having a leading edge and at least one recess extending through such leading edge into said metallic material. The end face further includes a plurality of flow paths, each of the leading edges of the upset having one such flow path extending therealong and inset therefrom. At least some of the upsets have a plurality of such recesses spaced therealong. A plurality of circulation ports open through the end face of the bit body, the number of circulation ports being less than the number of flow paths extending along the leading edges of the upsets, and at least some of the ports communicate with more than one such path. The bit further comprises a plurality of cutting structures carried by the bit body. Each cutting structure includes an elongate mounting body and a cutting formation on the exterior of the mounting body adjacent one end thereof. At least a majority of the mounting bodies of the bit are mounted in respective ones of the recesses in the upsets with their cutting formations facing outwardly along the leading edges of the upsets.

DRILL BIT

BACKGROUND OF THE INVENTION

It has become common practice to dress drag type well drilling bits with cutting elements made of polycrystalline diamond compacts, or "PDC." Unlike a roller type drill bit, which primarily crushes the earth formation being drilled, a drag type bit more typically actually cuts or chips the earth formation. Thus, the use of diamond in the cutting elements is especially important in drag type bits in order to increase their life. The polycrystalline diamond material typically is supplied in the form of a relatively thin layer on one face of a substantially larger mounting body. The mounting body is usually stud-like in configuration, and formed of a relatively hard material such as sintered tungsten carbide. The diamond layer may be mounted directly on the stud-like mounting body, or it may be mounted via an intermediate disc-like carrier, also comprised of sintered tungsten carbide. In any event, the diamond layer is disposed toward one end of the stud-like mounting body, the other end of which is mounted in a bore or recess in the body of the drilling bit.

The bit body itself may be formed of a tungsten carbide matrix. Traditionally, drag bit bodies have also been made of various forms of steel. One problem which has been associated with the use of PDC type cutting members in such drag bit bodies has been damage to and/or loss of these cutting members. This may occur by cracking and shearing of the stud-like mounting body, which carries the diamond layer, near the outer surface of the bit body. Cutting members may also be lost when the mounting bodies become completely dislodged from the recesses in which they are mounted.

U.S. Pat. No. 4,244,432 discloses one form of prior drag bit. Although the bit has a pin and substructure of metal, it is essentially a tungsten carbide matrix type bit in that it comprises a thick layer of such matrix forming the operating end face and extending inwardly therefrom so that the recesses for mounting of the cutting members, as well as the circulation port system, are all formed of the tungsten carbide matrix. This outer matrix portion of the bit has a stepped configuration which, to a certain extent, provides improved support for the stud-like mounting bodies of the cutting members. However, the use of tungsten carbide matrix material for forming any substantial part of a bit body entails a number of disadvantages. In the first place, the tungsten carbide matrix material is per se relatively expensive. Furthermore, while highly wear resistant, this material lacks resiliency and is relatively susceptible to cracking and similar type damage. This last characteristic effectively limits the types of manufacturing procedures which may be utilized in forming matrix type bits. For example, any substantial amount of machining of such bits is highly impractical, and the essential configuration of the matrix body must be achieved by other techniques, essentially analogous to casting. Furthermore, it is extremely difficult to mount the cutting members in the recesses in the matrix bit body with an interference fit without damaging the bit body, the cutting members or both. Therefore, as a practical matter, the mounting bodies of the cutting members must be brazed into the recesses in the bit body. These more complicated manufacturing techniques, which are necessitated by the use of tungsten carbide matrix in the bit body, further increase the cost of the bit. Indeed, successful

manufacturing of matrix type bits requires particular skill, expertise, and "art" not typically possessed by the average shop hand. Still another disadvantage of the matrix type bit body is its relatively poor thermal conductivity.

A number of the above disadvantages of matrix type bit bodies could, at least theoretically, be ameliorated by the use of a generally non-frangible metallic material, such as a suitable steel, for use in forming the bulk of the bit body. However, although there have been numerous efforts, beginning in the early to mid 1970's, to develop steel body drag bits with PDC cutting members, such efforts have not been entirely successful and, in particular, have not provided an adequate solution to the problem of damage and/or loss of the cutting members in use. Some of the earliest steel body PDC bits included a number of bores each with a concentric counterbore, the pairs of bores being located at various positions about the operating or cutting face of the bit body. The innermost bore of each pair provided the recess for mounting of the stud-like mounting body of the cutting member, whereas the larger but shallower outer bore provided access to the entirety of the diamond cutting face, theoretically for cooling and cleaning by the drilling mud. However, it was found that the mounting bodies of the cutting members on such bits did tend to crack or shear off as described hereinabove. Furthermore, the cooling and cleaning of the cutting faces by the drilling mud with such arrangements was less than satisfactory.

U.S. Pat. Nos. 4,323,130 and 4,265,324 illustrate efforts to improve upon the last-mentioned design by providing eccentric, rather than concentric, counterbores. Although these eccentric arrangements provided some additional support for the mounting body of the cutting member in the area opposite the cutting face, still further improvements were desired. Additionally, the eccentric counterbore scheme did not significantly improve the cooling and cleaning characteristics of the more basic concentric counterbore arrangement.

SUMMARY OF THE INVENTION

The present invention is concerned primarily with solving the problems previously encountered in metallic body drag bits utilizing PDC type cutting members and, more particularly, with specific attention to full bore, as opposed for example to core head, type well drilling bits. The present invention not only alleviates the problems previously associated with these types of bits, but further positively utilizes the characteristics of the steel or other generally non-frangible metal of the bit body to provide even further advantages. Nevertheless, certain aspects of the present invention can also be advantageously employed in other types of bits, such as tungsten carbide matrix bits.

A bit according to the present invention comprises a bit body having an operating end face whose general configuration or profile includes a plurality of upsets each having a leading edge surface and at least one recess extending through such leading edge surface. The profile of the end face of the bit body further comprises a plurality of flow paths. Each of the leading edge surfaces of the upsets has one of these flow paths extending therealong and inset therefrom. As indicated hereinabove, it is preferably that the bit body be comprised of a generally non-frangible metallic material, such as steel, such material essentially defining the

3 aforementioned profile, with the recesses extending into such metallic material. It is also preferable that at least some of the upsets have a plurality of such recesses spaced therealong.

The bit further comprises a plurality of cutting members carried by the bit body. Each of these cutting members includes an elongate mounting body and a cutting formation on the exterior of the mounting body adjacent one end thereof. At least a majority of the mounting bodies on the bit are mounted in respective ones of the recesses in the upsets with their cutting formations facing outwardly along the leading edge surfaces of the upsets.

This upset arrangement, with the recesses extending into the leading edge surfaces of the upsets, makes it possible to provide much better support for the end of the mounting body carrying the cutting formation. For example, that end of the mounting body may be embedded in and supported by the aforementioned metallic material not only on the trailing side generally opposite the cutting formation but also in lateral areas adjacent the cutting formation. For example, in preferred embodiments, the walls of the recess abut the respective mounting body about significantly more than 180° of its periphery measured in a plane transverse to the cutting face or cutting formation. This structural relationship helps to alleviate the cracking and shearing problems described above, and these problems are further remedied by the use of a non-frangible metallic material such as steel which, unlike a tungsten carbide matrix, is relatively resilient and can give to accommodate the forces imposed on the cutting member.

30 The upsets are preferably in the form of elongate ribs, each arranged to have a substantial radial component of direction, with respect to the end face of the bit body, at each point along its length. For those cutting members whose mounting bodies are mounted in recesses in these ribs, the cutting formations are fully exposed along the leading edge surfaces of the ribs, without the need for individual counterbores. The cutting formations may be generally planar cutting faces, and the bit body has a plurality of circulation ports opening through its end face. The number of such ports is preferably less than the number of flow paths extending along the leading edges of the ribs, and at least some of the ports communicate with more than one such flow path.

This arrangement, with relatively few ports, permits relatively high volume flow through each port, while the rib and flow path arrangement and its relationship to the ports organizes and directs the fluid flow to ensure improved cleaning and cooling of the cutting faces. The use of the elongate flow paths, as opposed to individual counterbores about each cutting member, also tends to reduce the problem of erosion of the bit body in the areas forward of the cutting members. Furthermore, for those cutting members whose mounting bodies are mounted in recesses in the ribs, each of the cutting faces lies generally coplanar to the next adjacent cutting face or faces on the same rib. Thus, the cutting faces themselves help to direct the fluid flow across one face and onto the next adjacent one. Additional cooling is provided by heat conduction through the metallic bit body, particularly enhanced by the substantial contact of this metallic material about a large portion of the periphery of the outer end of the mounting body of the cutting member, as described above.

The fact that there are relatively few circulation ports also permits each such port (or the nozzle therein)

to have a relatively larger inner diameter, thereby reducing the possibility of clogging of the ports.

The use of a generally non-frangible metallic material also facilitates the manufacturing procedure by permitting the use of relatively easy machining processes to form the ribs and flow paths, recesses, and circulation ports. It is then also possible to mount the mounting bodies of the cutting members in their respective recesses with interference fits, e.g. by press fitting or shrink fitting.

It is a principal object of the present invention to provide an improved metallic body full bore drag bit designed to provide enhanced support for the outer ends of PDC type cutting members.

Another object of the present invention is to provide for improved cooling and cleaning of the PDC cutting members in such a bit by both convection and conduction.

20 Another object of the present invention is to provide improve fluid flow characteristics in and over a drag type drilling bit.

Still another object of the present invention is to provide a full bore drag type bit which is more effective, and yet less expensive to manufacture, than prior bits.

Still other objects, features and advantages of the present invention will be made apparent by the following detailed description, the drawings and the claims.

BRIEF DESCRIPTION OF THE DRAWINGS

FIG. 1 is an elevational view of a drill bit according to the present invention.

FIG. 2 is a plan view of the operating end face of the drill bit taken along the line 2—2 in FIG. 1.

FIG. 3 is a vertical cross-sectional view taken along the line 3—3 of FIG. 2.

FIG. 4 is a vertical cross-sectional view taken along the line 4—4 of FIG. 2.

FIG. 5 is an enlarged detailed sectional view through 40 one of the ribs and recesses, showing the respective cutting member in elevation.

FIG. 6 is a detailed plan view taken along the line 6—6 in FIG. 5.

FIG. 7 is a detailed view taken along the line 7—7 in 45 FIG. 5.

FIG. 8 is a detailed view taken along the line 8—8 of FIG. 5.

FIG. 9 is a detailed view, similar to that of FIG. 5, showing a modification.

FIG. 10 is a diagrammatic view taken along the line 10—10 of FIG. 4 illustrating a fluid flow pattern.

DETAILED DESCRIPTION

Referring first to FIGS. 1 and 2, there is shown a full bore drag type drill bit according to the present invention. The bit includes a bit body 10 formed of steel or similar generally non-frangible metallic material, preferably having significant resiliency, as compared for example to tungsten carbide material, and also having relatively high heat conductivity. The bit body defined by such metallic material includes an uppermost pin 12 for connecting the bit to the lower end of a drill string. Below pin 12 is a neck 14 having bit breaker slots 16 which may be engaged by a suitable bit breaker plate for making up or breaking out the aforementioned connection to the drill string. Below neck 14, the bit body 10 widens to form a stabilizer section including alternating stabilizer blades 18 and junk slots 20. Stabilizer blades

18 have buttons 22 of hard material such as tungsten carbide embedded therein to help reduce wear.

The lowermost end of bit body 10 defines the cutting or operating face 24, best shown in FIG. 2. Face 24 of the bit body includes a number of upsets in the form of ribs 26a-26m. The innermost ends of these ribs are located at various distances from the centerline of the bit body, each rib extending generally outwardly from its respective inner end in a direction which, while not truly radial, has a substantial radial component with respect to end face 24 of the bit body. Each of the ribs 26a-26m is continuous with a respective one of the stabilizer blades 18.

Each of ribs 26a-26m has a respective leading edge surface with respect to the intended direction of rotation of the bit. For example, the leading edge surface of rib 26a is shown at 28a, and the leading edge surface of rib 26c is shown at 28c. For convenience, these leading edge surfaces will be referred to herein as being "generally perpendicular" to the overall profile of end face 24, shown in FIG. 4, and thus to the profile of the earth formation being drilled. This term is used only in the most general sense, and should not be construed as excluding bits in which the ribs and their leading edge surfaces have some rake angle.

Alternating between ribs 26a-26m are a plurality of channel-like flow paths 30a-30m. Each of these flow paths extends along the leading edge surface of a respective one of the ribs 26a-26m, and is inset from that rib. Each of the flow paths 30a-30m is also continuous with a respective one of the junk slots 20 in the stabilizer portion of the bit body. Each of the ribs 26a-26m has at least one recess 32 opening through its leading edge surface and extending into the metal of the bit body. In the embodiment shown, each of the recesses 32 opens not only through the leading edge surface of its respective rib, but also opens generally axially outwardly through the outermost part of the rib, the opening of the recess traversing the corner formed between the leading edge surface and the longitudinally outermost surface of the rib. Although some of the shorter ribs have only a single recess therein, as shown in FIG. 2, at least some of the ribs, such as ribs 26a, 26c and 26e, have an array of recesses spaced therealong.

The bit further comprises a plurality of cutting members 34. An exemplary one of these cutting members, specifically one of those associated with rib 26a, is shown in detail in FIGS. 5-8. The cutting member 34 includes an elongate stud-like mounting body 36 formed of a hard material such as sintered tungsten carbide. Mounting body 36 has one end mounted in a respective one of the recesses 32. The opposite end of member 36 extends outwardly through the mouth of the recess 32. Adjacent said outer end of the mounting body 36 and, more specifically, on that side which faces outwardly through the respective leading edge surface 28a of the rib 26a, there is mounted, as by bonding, a disc-shaped carrier 38, also formed of sintered tungsten carbide. On the outer surface of carrier 38 there is a layer 40 of polycrystalline diamond material, which serves as the cutting formation or cutting face of member 34. Although cutting face 40 may have a suitable vertical or horizontal rake angle, it is arranged to face outwardly along, and lie generally parallel to, the respective leading edge surface 28a of the rib in which member 34 is mounted. Preferably, the mounting body 36 is interference press fitted into its recess 32. In order to key the cutting member to the proper orientation, with cutting

face 40 facing outwardly through the leading edge 28a of rib 26a, the trailing side of the mounting body 36 and recess 32 are provided with small opposed grooves for receipt of a key pin shown at 42 in FIGS. 5 and 6. Alternatively, it is possible to provide only the groove in body 36, as the material of the bit body will be deformed into this groove during the interference fitting process to form an integral key.

By placing the opening of recess 32 in leading edge 28a and, more specifically, at the outermost corner of such leading edge, it is possible to allow full exposure of cutting face 40 through such leading edge without a counterbore about recess 32, while a significant portion of the adjacent outermost end of mounting body 36 is embedded in and supported by the metallic material of rib 26a. By comparison of FIGS. 5, 6 and 7, it can be seen that, at the outer end of mounting body 36, not only the trailing side 36a opposite cutting face 40, but also lateral portions 36b generally adjacent face 40 and its carrier 38 are thus embedded and supported. Indeed, it can be seen that the walls of recess 32 abut the outer end of the mounting body 36 about significantly more than 180° of its periphery, when viewed in a plane transverse to cutting face 40 (see FIGS. 6 and 8). This relatively large amount of abutment and support near cutting face 40 helps to prevent cracking and/or breaking of mounting body 36 in use, and this effect is further enhanced by the inherent resiliency of the steel of which the bit body is formed, which can give to accommodate the forces imposed on the cutting member 34 in use.

In finished form, the bit body is coated with a thin layer 44 of tungsten carbide matrix or the like. However, this coating 44 is sufficiently thin that it does not significantly affect the aforementioned advantages of the use of steel to form the major part of the bit body. More specifically, it can be seen that the recess 32 extends into the steel, and that the steel defines the bulk of rib 26a and, in particular, the portion which supports the outer end of mounting body 36.

Each of the other cutting members 34 is similarly mounted in a respective one of the recesses 32 in the various ribs 26a-26m. The cutting members of adjacent ribs are staggered in the generally radial direction, so that each cutting face 40 traverses the earth's formation at a slightly different distance from the centerline of the bit, and together, the cutting faces 40 cover substantially the entire end of the borehole in use.

Referring now again to FIG. 2, further in conjunction with FIGS. 3 and 4, a plurality of circulation ports 46, 48, 50 and 52 open through end face 24 at varying distances from its centerline each in communication with several of the flow paths 30a-30m. Each of these ports is defined by a rectilinear bore which intersects the larger central bore 54 of the bit body. Each of these smaller rectilinear bores is provided with a removable nozzle fitting. As shown in FIG. 3, the fitting 56 for innermost bore 46 is sealed with respect to that bore by an O-ring 58 carried in an annular groove in the bit body. Nozzle fitting 56 has an external annular groove 60. A nail 62 extends through groove 60 and is also received in an aligned internal groove in bore 46 to removably mount nozzle 56 in that bore in a manner already known in the art. The remaining nozzle fixtures are exemplified by fixture 64 shown in FIG. 4. Nozzle 64 is bottomed against a shoulder formed in bore 50. The outermost part of bore 50 is further enlarged and

tapped to receive an externally threaded retaining ring 66 for nozzle 64.

Still referring to FIG. 4, the central portion of end face 24 of the bit body is inwardly concave, more specifically having a generally conical profile. Each of the circulation ports, other than the innermost port 46, has a centerline which intersects the end face 24 of the bit body (and thus the corresponding end face of the bore-hole) at an angle of about 0° to 40° from the normal to end face 24 at that point. This causes fluid emerging from the port to tend to disperse in a somewhat egg-shaped pattern as shown in FIG. 10. Thus, the tendency is for the major part of the fluid emerging from the port to flow radially outwardly through the adjacent flow path or paths 30a-30m and carry cuttings upwardly through junk slots 20.

Each of the circulation ports 46, 48, 50 and 52 communicates with more than one of the flow paths 30a-30m. Thus, only four ports can adequately service 12 flow paths and an equal number of ribs. Such a relationship, i.e. with the number of ports being less than the number of flow paths and ribs, is preferred since it allows a greater volume of flow through each of the ports and for each nozzle to have a sufficiently large I.D. to ensure against clogging.

The alternating ribs and flow paths, with the latter communicating with the circulation ports, and the former carrying the cutting members such that the cutting faces 40 face into said flow paths, organizes the fluid flow to best insure that each cutting face 40 is washed 30 and cooled by the circulating fluid. Indeed, the cutting faces 40 themselves on each respective rib lie generally parallel, and more specifically nearly coplanar, to the adjacent cutting face or faces on the same rib so that each cutting face tends to direct the fluid thereacross 35 and toward the next adjacent cutting face. In this sense, "parallel" and "coplanar" are used in a very general sense. Thus, the ribs 26a-26m could be provided with a slight curvature, with the cutting faces shifted accordingly, and the adjacent cutting faces on such a rib would 40 still be considered generally "parallel" and "coplanar."

The cutting members are further cooled by conduction of heat through the steel of the bit body, and this effect is enhanced by the substantial abutment of the outer ends of the mounting bodies of the cutting members by their respective recess walls as described hereinabove.

The steels and similar metals preferably used for bit body 10, unlike tungsten carbide matrix, are easily machinable to form the alternating rib/channel pattern of 50 the end face as well as the bores 46, 48, 50, 52 and 54. Such metals also readily permit attachment of bodies 36 by interference fits.

Cutting members could be provided in other forms than those shown in FIGS. 1-8, in which case the configuration of the recesses would be altered accordingly. However, it is always desirable that the mouth of the recess open through the leading edge surface of the respective rib, more specifically at the outermost corner thereof, and extend into the metallic material of the rib. 55 For example, FIG. 9 shows a variation in which the diamond layer 40' is applied more nearly on the axial end of mounting body 36', rather than in a more lateral orientation. It can be seen how the orientation of recess 32' in rib 26a' has been correspondingly altered, so that the mouth of the recess still opens through the leading edge surface 28a'. Another variation illustrated in the embodiment of FIG. 9 is the application of the diamond

layer 40' directly to the stud-like mounting body 36', rather than on an intermediate carrier disc such as 38 of the preceding embodiments.

Other modifications will suggest themselves to those of skill in the art. For example, in the preferred embodiment shown, the profile of the end face of the bit body is such that all cutting members 34 may be mounted in the ribs 26a-26m. In other designs, e.g. with relatively wider flow paths and fewer ribs, some cutting members 10 may be mounted elsewhere than in the ribs. However, it is nevertheless desirable that at least a majority of the cutting members be mounted in the ribs. In other modifications, the upsets may be in forms other than elongate ribs. Materials, preferably super hard materials such as 15 cubic boron nitrate or boron carbon, may be used as alternatives to the diamond layers described above. Accordingly, it is intended that the scope of the present invention be limited only by the claims which follow.

What is claimed is:

1. A full bore drag type well drilling bit adapted for rotation in a given direction comprising:

a bit body comprised of a generally non-frangible metallic material, said bit body having an operating end face the general configuration of which is defined by said metallic material to include a plurality of upsets each having a leading edge surface and at least one recess extending through each such leading edge surface into said metallic material, said end face of said bit body further comprising a plurality of inset flow channels each having a pair of side walls disposed respectively on the leading and trailing sides thereof, each of said leading edge surfaces of said upsets having a respective one of said flow channels extending therealong, said leading edge surface and the trailing side wall of said respective flow channel forming a common surface facing generally into said direction of rotation and extending to the bottom of said channel;

and a plurality of cutting members carried by said bit body, each of said cutting members comprising an elongate mounting body and a cutting formation on the exterior of said mounting body adjacent one end thereof, at least a majority of said mounting bodies being mounted in respective ones of said recesses with their cutting formations facing outwardly from the respective leading edge surfaces generally toward the respective flow channels and generally fully exposed along said leading edge surfaces whereby said cutting formations are disposed at least partially in the respective flow channels;

each of said flow channels having a length extending generally parallel to said side walls and a width extending between said side walls, said width being generally uniform along a substantial portion of said length, and said generally uniform width further being generally on the order of magnitude of the dimensions of said cutting members measured in said direction of rotation.

2. The apparatus of claim 1 wherein at least some of said upsets have a plurality of such recesses spaced therealong, with a respective mounting body mounted in each such recess.

3. The apparatus of claim 1 wherein the other end of each of said mounting bodies which is mounted in one of the recesses in said upsets is substantially spaced from said cutting formation along the length of said mounting body, and said cutting formation comprises a cutting

face disposed generally to one side of said mounting body.

4. The apparatus of claim 3 wherein each of the mounting bodies which is mounted in one of the recesses in said upsets has a significant portion of said mounting body opposite said cutting formation embedded in and supported by the metallic material in the respective one of said upsets.

5. The apparatus of claim 4 wherein each of the mounting bodies which is mounted in one of said recesses in said upsets has lateral portions of said mounting body adjacent said cutting formation at least partially embedded in and supported by the metallic material in the respective one of said upsets.

6. The apparatus of claim 5 wherein the walls of each of said recesses about the respective mounting body about more than 180° of its periphery measured in a plane transverse to and intersecting said cutting formation.

7. The apparatus of claim 6 wherein said mounting bodies are mounted in said recesses by interference fits.

8. The apparatus of claim 6 wherein said upsets are elongate ribs each arranged to have a substantial radial component of direction, with respect to said end face of said bit body, at each point along its length.

9. The apparatus of claim 1 wherein said upsets are elongate ribs each arranged to have a substantial radial component of direction, with respect to said end face of said bit body, at each point along its length.

10. The apparatus of claim 9 wherein said bit body has circulation port means opening through said end face and communicating with said flow channels.

11. The apparatus of claim 10 wherein said circulation port means comprises a plurality of circulation ports, the number of said ports being less than the number of flow channels extending along said leading edge surfaces of said ribs, each of said ports having more than one such flow channel extending radially outwardly therefrom and communicating therewith.

12. The apparatus of claim 11 wherein said cutting formations comprise cutting faces.

13. The apparatus of claim 11 wherein, for those cutting members whose mounting bodies are mounting in said recesses in said ribs, each of the cutting faces lies generally coplanar to the next adjacent cutting faces on the same rib.

14. The apparatus of claim 13 wherein said bit body has a central longitudinal bore, and wherein said ports are defined by rectilinear bores intersecting said central bore.

15. The apparatus of claim 14 wherein each of the centerlines of said rectilinear bores intersects said end face of said bit body at an angle of about 0° to 40° from the normal to the bit body at the point of such intersection.

16. The apparatus of claim 15 wherein each of said ports is located a different radial distance from the centerline of said bit body.

17. The apparatus of claim 16 wherein said end face of said bit body is inwardly concave.

18. The apparatus of claim 11 wherein each flow path which extends along one of said leading edge surfaces communicates directly with one of said circulation ports.

19. The apparatus of claim 11 further comprising nozzle fixtures mounted in said ports.

20. The apparatus of claim 19 wherein said nozzle fixtures are removable.

21. The apparatus of claim 1 wherein said mounting bodies are comprised of tungsten carbide, and wherein

said cutting formations comprise cutting faces defined by polycrystalline diamond layers carried on said mounting bodies.

22. The apparatus of claim 21 wherein said polycrystalline diamond layers are carried on respective ones of said mounting bodies via intermediate carrier elements.

23. The apparatus of claim 1 further comprising a relatively thin coating of hard material, comprising tungsten carbide, overlying said metallic material of said bit body.

24. The apparatus of claim 1 wherein said bit body is comprised of steel.

25. A full bore drag type well drilling bit adapted for rotation in a given direction comprising:

a bit body comprised of a generally non-frangible metallic material, said bit body having an operating end face the general configuration of which is defined by said metallic material to include a plurality of upsets each having a leading edge surface and at least one recess extending through each of said leading edge surfaces into said metallic material, said end face further comprising a plurality of inset flow channels each having a pair of side walls disposed respectively on the leading and trailing sides thereof, each such leading edge surface of an upset having a respective such flow channel extending therealong, said leading edge surface and the trailing side wall of said respective flow channel forming a common surface facing generally into said direction of rotation;

a plurality of cutting members each comprising an elongate mounting body and a cutting formation on the exterior of said mounting body adjacent one end thereof, each of said mounting bodies being mounted in a respective one of said recesses with said cutting formation facing outwardly from the respective leading edge surface generally toward the respective flow channel and generally fully exposed along the leading edge surface of the respective one of said upsets whereby said cutting formations are disposed at least partially in the respective flow channels, the walls of each of said recesses abutting the respective mounting body about more than 180° of its periphery measured in a plane transverse to and intersecting said cutting formation;

each of said flow channels having a length extending generally parallel to said side walls and a width extending between said side walls, said width being generally uniform along a substantial portion of said length, and said generally uniform width further being generally on the order of magnitude of the dimensions of said cutting members measured in said direction of rotation.

26. The apparatus of claim 25 wherein at least some of said upsets have a plurality of such recesses spaced therealong, with a respective mounting body mounted in each of said recesses.

27. The apparatus of claim 26 wherein said mounting bodies are mounted in said recesses by interference fits.

28. The apparatus of claim 27 wherein said bit body is comprised of steel.

29. The apparatus of claim 25 wherein the other end of each of said mounting bodies which is mounted in one of the recesses in said upsets is substantially spaced from said cutting formation along the length of said mounting body, and said cutting formation comprises a cutting face disposed generally to one side of said mounting body.
